UNITED STATES PATENT OFFICE.

FRANCISCO GONZALEZ AND MIGUEL SUAREZ, OF HABANA, CUBA.

APPARATUS FOR IRONING HATS.

Application filed June 12, 1922. Serial No. 567,731.

To all whom it may concern:

Be it known that we, FRANCISCO GONZALEZ and MIGUEL SUAREZ, subjects of the King of Spain, residing at Habana, Cuba, Sol No. 123, have invented a new and useful Improvement in Apparatus for Ironing Hats; and we do hereby declare the following to be a full, clear, and exact description of the same.

10 This invention relates to an apparatus for ironing hats and has as its principal object to provide an apparatus to iron hats and especially straw hats, the construction of which permits of the ironing operation being effected in a quicker and more advantageous manner than could be done with devices hitherto known.

Another object is to provide an apparatus to iron hats wherein the ironing elements 20 are provided both with hydraulic and mechanical pressure.

Another object is to provide an ironing element which exercises a graduated pressure inside of the top of a hat placed in the last.

Further advantages will be deduced from the following specification describing the invention in detail and from the accompanying drawings illustrating an embodiment 30 thereof and in which:

Fig. 1 is a side elevation of the apparatus forming the subject of this invention.

Fig. 2 is a top plan view of the same.

Fig. 3 is a vertical section to an enlarged 35 scale on line 3—3 of Fig. 2.

Fig. 4 is a horizontal section to an enlarged scale on line 4—4 of Fig. 1.

Fig. 5 is a horizontal section to an enlarged scale on line 5—5 of Fig. 1.

Fig. 6 is a horizontal section on line 6—6 of Fig. 1.

Fig. 7 is a top plan view of the female last used in the apparatus.

Fig. 8 is a perspective view of the male last used in the apparatus.

Fig. 9 is a partial vertical section of the upper portion of the apparatus showing one operative stage of the same.

In these figures is shown a rectangular 50 platform 1 supported by legs 2 on which is positioned a casing 3 of horizontal oval cross section having at its base a projecting horizontal flange 3' provided with lugs 3'' for receiving screws 4 to screw the casing to the platform. Casing 3 has an upper projecting horizontal flange 5 below which are

ventilating bores 6. Inside the casing 3 is a gas burner 7 having outlets 8 and fed by a supply pipe 9 passing through bore 8' in the casing 3. The casing 3 forms a support for 60 a female last 10 formed in the shape of the desired straw hat and including a horizontal flange 10' corresponding to the hat brim. The flange 10' rests on the flange 5 of the casing. The bottom of last 10 is positioned 65 adjacent the burner 7.

In the center of platform 1 is a threaded bore 11 receiving a vertical screw 12 having at its lower end a handle 13 and at its upper end a disk 14 which is held in position by a 70 collar 15, the disk serving as a support for the last 10.

On platform 1 is a standard comprising two supports 16 carrying an upper cross bar 17 connected to the supports by screws 18. 75 The supports 16 carry vertical guide members 19 slidably receiving a movable frame carrying the male last and including a transverse member 20. The ends of member 20 have enlargements 20' carrying reduced portions 20'' receivable in the vertical guides 19. The central portion of member 20 is formed as shown at 21 in an arc and presents members 21' terminating at the bottom in a horizontal rectangular plate 22 which is shown in 80 Fig. 4 with front and rear curved recesses 22'. In the corners of the plate are bores receiving the threaded upper ends of four straight legs 23 which are secured to the top of the plate by means of nuts 24 and at the lower 85 ends are fixed to the portions of a second horizontal plate 25 which as shown in Fig. 5 has lugs 25' furnished with elongated slots 25''. In the center of plate 25 is an oval aperture 26. Beneath plate 25 is a hollow 90 body 27 open at both the top and bottom and having a portion matching the outline of plate 25. On the body 27 at its upper edge are projecting stems received in the seats 25'' of plate 25 for securing the two members 100 together by wing nuts 28 threaded to the ends of said stems. The body 27 has also offset lugs 29 projecting in a horizontal plane, to which lugs is attached an element 31 by means of bolts 30. This element 31 105 is preferably made of aluminum and is formed to match the brim of a hat to be ironed.

Encircling body 27 is an annular gas burner 32 having an inlet tube 32' which is 110 connected to the same gas generator as the feed pipe for gas burner 7 described above.

In the center of plate 22 is a bore 33 which receives an internally threaded sleeve 34 so as to permit rotary movement but to prevent axial movement. On sleeve 34 are spaced horizontal flanges 34' fitting above and below the faces of the plate 22. Received in the sleeve 34 is a screw 35 having an operating handle 36 formed integrally with the sleeve 34. In screw 35 there is a central aperture 37 extending the full length thereof and also through a plate 38 connected to the lower end of the screw, said plate having its lower edges beveled as shown in Fig. 3. On plate 38 are outstanding lugs 39 which fit into bores 40 in the lower face of an annular plate 41. In plate 41 is an edge channel 42 forming a beveled peripheral flange 42'. Between the plates 38 and 41 is secured the inturned edge of a hollow body 43 closed at its lower end and constituting the male member of the last 10. This member 43 is made of flexible impermeable material such as rubber and is firmly held between the plates 38 and flange 42' of plate 41 by means of a nut 40' mounted onto screw member 39 and bearing against the upper surface of plate 41. To the upper end of screw 35 is attached a collar 45 connected to a flexible tube 46 which communicates with a pump 47 for feeding water through the screw member. The pump is operated by a lever 47' and receives its feed water from a tank 48 separate from the apparatus and underneath the same. Water injected into member 43 is conducted away from the same by means of a branch pipe 49 connected to the inlet tube 46 and discharging into tank 48. The outlet tube 49 is normally closed by a valve 50 suspended from a rod 50' and operated by a hand lever 51 pivoted at 52 at the outside of one of the members 16. At 46' is a pressure indicator connected to the upper end of a branch pipe 46'' which communicates (not shown) with the feed pipe 46.

The frame carrying the male last 43 and member 31 is operated between guides 19 by means of depressing a pedal 52 connected at its rear end to a cross bar 53 which is held between extensions 54 of legs 2. Near the center pedal 52 is fixed to a cross bar 54 to the ends of which cross bar are connected the lower ends of rods 55 the other ends of which rods connect with arms 56 carrying a hub 56'. This hub receives a transverse horizontal axle 57 having a bearing in legs 2 in a plane above that of the cross bar 53. Counterweights 59 are connected to the hubs 58 as shown in Fig. 3. Outside of levers 55 two vertical rods 60 are connected to the cross bar 54 to which cross bar they are held by pins 61. The upper ends of hubs 60 are connected to the portions 25 of member 20 by means of screws 62.

At the middle of cross member 20 there

is a threaded collar 63 which receives the lower threaded end of a vertical rod 64 having a smooth upper portion passing through a bore 65 in bar member 17 of the supporting standard and projects beyond the upper face of the bar 17. Rod 64 carries a handle for sliding it in the bore 65. At the central part of member 17 is an enlarged hollow member 67 carrying a horizontal axle 68 supported in bearings 67'' and 68' and retained inside the enlargement 67 by means of collars 67' fixed thereto. On axle 68 a block 69 is eccentrically mounted which block has a cam convex surface. The axle 68 can be rocked in its bearings by means of a lever 70 pivoted at 71 to the inner face of one of the members 16 of the standard. At the end of lever 70, at 72, there is connected a pivoted rod 73 attached at its upper end to a link 75 which link is in turn fixed to the axle 68.

The operation of the above described device is as follows:

The various parts being considered in the position shown in Fig. 3, a hat 76 is placed within the female last 10, the brim of the hat resting on flange 10'. Operating member 13 is rotated to advance the support 14 until it bears firmly against the lower part of last 10. The gas burners 7 and 32 which respectively heat the last 10 and body 27 are now lighted. The hand wheel 66 is then rotated to adjust the relative position of the two last members. Next the pedal 53 is depressed against the resistance of counterweights 59 to cause the supporting frame to slide downwardly between the guides 19 and thus bring the male last together with the member 31 toward last member 10. This motion is continued until the two last members are brought into engagement to hold a hat between the same, the hat brim being compressed between members 31 and 10'.

Handle 36 is then operated so as to force the last 43 downwardly to a greater or lesser extent according to the height of the crown of the hat to be ironed. Then the pump 47 is placed in operation by means of lever 47' and operates to inject the necessary quantity of water inside the last 43 so as to produce the necessary pressure against the top and sides of the crown of the hat. The pressure gauge 46' will indicate when the required pressure has been reached.

Next the lever 70 is depressed to cause cam member 69 to swing downwardly and depress rod 64 to a greater or lesser extent according to requirements, as shown in Fig. 9. This results in a further and final compression between the two last members. As soon as the pedal 52 and lever 70 are released, the parts are all returned to their original positions, the hat is removed from the last and the process is repeated as set

forth above. In order to exhaust the water from last 43' to relieve pressure in such last, lever 51 is depressed to open the valve 50 at the outlet end of pipe 49.

- 5 It will be noted that the various parts forming the male and female lasts are removable and can be readily interchanged for other last members of different sizes suitable for different sized and shaped hats.
- 10 It is of course evident that various changes can be made in the construction as described above without departing from the spirit of this invention except as prescribed by the appended claims.
- 15 We claim—
  1. An apparatus for ironing hats, comprising, a supporting structure, a male last, a female last, a movable frame carried by the supporting structure and carrying the male last, frame moving mechanism for interengaging the lasts, and a second means for forcing the lasts together, said second means comprising, a threaded shaft adjustably threaded into said movable frame, and having a smooth portion slidable in an apertured portion of the supporting structure, and means for exerting pressure on the free end of the threaded shaft, whereby to force the lasts into closer engagement, the last said means comprising, a pivoted operating lever, a pivoted shaft positioned adjacent the apertured portion of the supporting structure, a link connection between the operating lever and pivoted shaft, and a cam member, carried by the pivoted shaft, and operable by the operating lever, to bear against the end of the threaded shaft.
  - 20 2. An apparatus for ironing hats, comprising, a supporting structure, a male last, a female last, a movable frame carried by the supporting structure and carrying the male last, frame moving mechanism for interengaging the lasts, and a second means for forcing the lasts together, the male last having cooperating fluid pressing means, said second means comprising, a threaded shaft adjustably threaded into said movable frame, and having a smooth portion slidable in an apertured portion of the supporting structure, and means for exerting pressure on the free end of the threaded shaft, whereby to force the lasts into closer engagement, the last said means comprising, a pivoted operating lever, a pivoted shaft positioned adjacent the apertured portion of the supporting structure, a link connection between the operating lever and pivoted shaft, and a cam member, carried by the pivoted shaft, and operable by the operating lever, to bear against the end of the threaded shaft.
  - 25 3. An apparatus for ironing hats, comprising, a supporting structure, a male last, a female last, a movable frame carried by the supporting structure and carrying the male last, frame moving mechanism for interengaging the lasts, and a second means for forcing the lasts together, said second means comprising, a threaded shaft adjustably threaded into said movable frame, and having a smooth portion slidable in an apertured portion of the supporting structure, and means for exerting pressure on the free end of the threaded shaft, whereby to force the lasts into closer engagement, the last said means comprising, a pivoted operating lever, a pivoted shaft positioned adjacent the apertured portion of the supporting structure, a link connection between the operating lever and pivoted shaft, and a cam member, carried by the pivoted shaft, and operable by the operating lever, to bear against the end of the threaded shaft.
  - 30 4. An apparatus for ironing hats, comprising, a supporting structure, a male last, a female last, a movable frame carried by the supporting structure and carrying the male last, frame moving mechanism for interengaging the lasts, and a second means for forcing the lasts together, said second means comprising, a pivoted operating lever, a pivoted shaft positioned adjacent the apertured portion of the supporting structure, a link connection between the operating lever and pivoted shaft, and a cam member, carried by the pivoted shaft, and operable by the operating lever, to bear against the end of the threaded shaft.

In testimony whereof, we have signed our names to this specification.

FRANCISCO GONZALEZ.
MIGUEL SUAREZ.
